J. Oltarsh, New York, N. Y.

Application March 29, 1934, Serial No. 51,214

Term of patent 3½ years

To all whom it may concern:

Be it known that I, HENRI JULES LAUN, a citizen of Germany, residing at 960 Greene Avenue, Brooklyn, New York, have invented a new, original, and ornamental Design for a Textile Fabric or Similar Article, of which the following is a specification, reference being had to the accompanying drawing, forming a part thereof.

The figure is a plan view of a textile fabric showing the complete width of the fabric to which my new design is applied except for the portion between the break lines which is similar to that

on either side thereof. The dot and dash lines on the drawing outline substantially the design unit which unit is repeated in regular succession as indicated by the extensions beyond the unit boundaries.

I claim:

The ornamental design for a textile fabric or similar article as shown and described.

In testimony whereof I have signed this specification.

HENRI JULES LAUN.
